UNITED STATES PATENT OFFICE

RICHARD P. WHITE, OF CHICAGO, ILLINOIS

DISPLAY VESSEL AND HINGE THEREFOR

Application filed April 20, 1928. Serial No. 271,634.

This invention relates to display vessels.

The principal object of the invention is the provision of new and improved means for mounting or hinging a cover or closure on a display vessel or the like.

Another object of the invention is the provision of new and improved means for detachably hingedly connecting a closure to a display or other vessel.

10 A further object of the invention is the provision of new and improved means for hingedly connecting a closure or lid of a display or other vessel and for holding the same in a plurality of adjusted positions.

15 A still further object of the invention is the provision of new and improved means for attaching the hinge to the hinge lug of a display jar.

Still another object of the invention is the provision of new and improved means for connecting a closure to a vessel and for holding the same in adjusted positions, that is simple in construction, easily assembled and adjusted, that is cheap to manufacture, ornamental in appearance, and that is not likely to become broken or deranged.

Other and further objects and advantages of the invention will appear from the following description taken in connection with the 30 accompanying drawings, in which

Fig. 1 is a side elevation of a display vessel with the hinge in position thereon;

Fig. 2 is a plan view thereof;

Fig. 3 is a vertical section through a portion of the display jar and the hinge lug showing the hinge in position thereon, with parts broken away;

Fig. 4 is a section in line 4—4 of Fig. 3;

Fig. 5 is a side elevation of the head portion of the stationary member of the hinge;

Fig. 6 is a plan view of a portion of a display vessel, showing a modified form of holder for the closure;

Fig. 7 is a section on line 7—7 of Fig. 6;

Fig. 8 is a view similar to Fig. 7, but showing a modified form of construction;

Fig. 9 is a vertical section of a modified form of display vessel, with the closure in 50 position thereon; and

Fig. 10 is a perspective view of a modified form of one of the hinge members.

In displaying foods and the like it is desirable that as far as practicable they be not directly exposed to the dust laden air of the store. In my copending application, Ser. No. 60,434, means were disclosed for employing a transparent closure for the vessel. The present invention contemplates the use of a transparent closure with a detachable hinge connection between the closure and the vessel whereby the closure may be readily removed as when the vessel is being cleaned or moved from one place to another.

Referring now to the reference characters, 65 10 designates a vessel which may be of earthenware, as shown in Fig. 1, or of any other suitable material. The vessel 10 is preferably cylindrical, as at 11, at its upper portion, tapered and reduced in diameter as at 12 at 70 its lower portion to provide a ledge or annular shoulder 13 extending about the vessel. The vessel is adapted to be placed in the top of a barrel with the tapered portion within the barrel and the shoulder 13 resting on the 75 top of the barrel staves.

In practice, when a barrel of edibles, such as pickles, is received, the vessel 10 is filled with the articles from the barrel, thus making room for the tapered portion 12 of the vessel, 80 after which the vessel is placed on top of the barrel for displaying the food products.

The vessel 10 is provided with a transparent lid, cover or closure 14 and suitable means are provided for mounting the lid on the vessel. In the form of mounting means selected 85 to illustrate one embodiment of the invention, the vessel is provided with a lug 15 having a vertical opening 16 therethrough.

The hinge designated generally by the reference character 17, for connecting the closure 14 to the vessel, comprises what for convenience will be termed a lower or fixed member 18 having a threaded shank member 19 for extending through said opening 16, and a movable member 20 which is adapted to be attached to the closure 14. The fixed member 18 is provided with a head 21 having an open slot 22 therein. For convenience of description the slot 22 will be referred to as 100

extending upwardly and rearwardly. The lower portion 30 of the head has an extension 23 which projects above the upper portion 24 to form a stop for the hinge as will 5 presently appear.

In the attachment of hinge members to integral lugs on jars or other frangible vessels, it is desirable that means be provided for preventing undue stress being placed on the 10 lug when the hinge is attached. These lugs are frequently broken off where the hinge member is clamped directly and positively to the lug, due to the excessive pressure that is likely to be inadvertently applied in screwing home the nut for holding the shank of the hinge in these lugs. In order to avoid applying excessive pressure to the lug, a spring 25 is placed on the lower end of the shank 19 of the hinge 17 that extends through 15 said opening 16 for attaching the hinge to the vessel. A nut 26 holds the parts in assembled relation. A conventional washer 27 may be inserted between the spring 25 and the lower side of the lug 15 for forming a seat for 20 said spring. One or more washers 28 of fiber or other yielding material may be and preferably are inserted between the shoulder 29 and the lug 15. The spring will also permit the movement of the shank 19 through the opening 16 when the lid is closed in the event that 25 it is too low to permit the lid to fit squarely on the vessel.

The upper or movable portion of the hinge is provided with a head 31 having a stud or 30 pin 32 which is adapted to engage in the slot 22 of the head 21. Preferably the head 31 is bifurcated, forming the furcations 33 and 34, see Fig. 4, and the stud 32 is secured at each end in said furcations. Preferably the 35 furcations are of such a length that the connecting portion 35 between them will form a stop for preventing the stud from being withdrawn from the slot 22, except when the closure 14 is in its elevated position. The connecting portion between the furcations 33 and 40 34 is also provided with a shoulder 36 which is adapted to engage the extension 23 as shown in dotted lines in Fig. 1 for limiting the rearward movement of the closure 14. The parts 45 are so constructed that when in its uppermost position the closure will be passed dead center so that it will be held by gravity in its elevated position.

Suitable means are provided for holding 50 the head in any desired adjusted position. As shown, a spring-pressed bolt 37 is provided for this purpose. The bolt 37 is slidably mounted in one of the furcations, as 34, and is provided with a conical end 38 for engaging 55 in the slot 22 for holding the closure in closed position, or is adapted to resiliently engage one of a plurality of recesses 39 on the head 30 for holding the closure in various adjusted positions. A spring 40 urges the bolt 60 inwardly and causes the bolt to automatically

engage the recesses 39 which are arranged in the arc of a circle. When the bolt engages the slot it must be retracted by hand. If desired, a manually operated threaded bolt 50 may be substituted for the spring-pressed bolt, as shown in Fig. 2. The movable member 20 of the hinge is provided on its forward portion with a recess or groove 41 for receiving one edge of the closure 14.

Preferably a cushioning member 42 is inserted between the glass and the sides and bottom of the groove. A holding member 43 is provided for holding the hinge member 20 in position on the closure. As shown, this member comprises a closure engaging portion 44 having a groove or channel 45 on its lower portion for engaging the forward edge of the closure 14. If desired, a cushioning member 46 may be inserted between the sides and bottom of the channel or groove 45 and the closure 14.

The closure 14 is clamped between the grooved portions of the members 44 and 20 by any suitable means as a rod 47 which may be threaded at one end into the hinge member 20 and its other end engage a socket in the member 44, the part being held in said socket in any suitable manner as by means of the screw 48 engaging the end of said rod. The means for attaching the hinge to the closure is shown and described in my co-pending application Ser. No. 60,434.

The closure engaging member 44 is provided with a projection 49 to which a spring clip 51 may be attached. The spring clip 100 is curved outwardly and then inwardly to form a loop for constituting a handle for raising and lowering the closure.

The inner end of the clip 51 is adapted to engage in a recess 52 in the cylindrical portion of the vessel 10. The hinged portion 20 is also provided with an upstanding lug having an inclined slot 53 therein for supporting a placard.

Rubber or other suitable gasket 54 may 110 be provided between the upper edge of the vessel and the closure for forming an air and dust tight joint. This gasket may be attached either to the closure or the upper edge of the jar. As shown, the jar is provided 115 with a recess 55 for receiving the lower edge of the gasket for holding the same in position.

The form of the device shown in Figs. 6 and 7 differs from that described above in 120 that different means are provided for holding the lid in adjusted position. As shown, the head 21^a of the fixed portion of the hinge is provided with a plurality of radial notches 56 which are adapted to be engaged 125 by the keeper 57 slidably mounted through the movable portion of the hinge and the closure clamping members. The closure engaging member 58 is provided with a bore through which the outer end of the clamping 130

rod 59 is adapted to extend. The parts are held in assembled relation by a nut 61. The clamping rod 59 is provided with an axial bore through which the keeper 57 is adapted to extend. The fixed portion of the hinge is also provided with a bore for receiving the inner end of the keeper.

The keeper 57 is held in projected position by a spring 62 which engages a pin 63 fixed in the keeper and which extends outwardly through a slot 64 in the clamping rod 59. The outer end of the keeper may be provided with the handle portion 65 for retracting the same.

15 A further modified form of the device is shown in Fig. 8. In this form of the device the keeper 66 is normally held out of contact with the notches 56 by the spring 67 encircling the clamping rod 59 and seating 20 against a pin 68 in the keeper 66.

Cam member 69 mounted on a stud 71 is adapted to engage the keeper 66 for forcing the same into engagement with said notches against the tension of the spring 67.

25 The cam member 69 is provided with a lip 72 for limiting the movement of said member in one direction. The parts are so arranged that when the cam member is in the position shown in Fig. 8, the cam member 30 will be on dead center and will hold the keeper in its extended position.

In Fig. 9 is shown the application of the closure to a vessel 73 formed of sheet metal. The vessel 73 has its upper edge rolled into 35 a bead as at 74 and the closure engaging member 44 is provided with a C-shaped spring clip 75 for engaging beneath said bead for holding the lid in closed position.

In Fig. 10 is shown a modified form of construction for attaching the hinge to the vessel. As shown, the head 21 of the fixed member 18 instead of being provided with an attaching shank portion, and with means for clamping the head in position on the vessel. 45 The lower or fixed member 18 of the hinge is rigidly secured to a sectional band 80 as by being integral therewith, or attached thereto by bolts or rivets. Preferably the ends of the band are turned outwardly as 50 at 81 and 82 and perforated for the reception of a clamping bolt 83 for clamping the band on a vessel.

In all forms of the device the parts are so constructed that when the retaining bolt 37 or 55 50 engages in the slot the closure cannot be removed from the vessel and the closure will be held in lowered position on the gasket 54.

It is thought from the foregoing taken in 60 connection with the accompanying drawings that the construction and operation of my device will be apparent to those skilled in the art, and that various changes in size, shape, proportion and details of construction may be made without departing from the spirit 65 and scope of the appended claims.

I claim as my invention:

1. In combination, a display vessel, a closure therefor, a hinge for said closure, said hinge comprising a hinge member secured to said vessel, a cooperating hinge member on said closure, a pivotal pin and slot connection between said members, and means for holding said closure in various adjusted angular positions.

2. In a display device, a display vessel having a cylindrical upper portion, a reduced tapered lower portion, a hinge lug having an opening therein on said upper portion, a closure for said vessel, a hinge for said closure, said hinge comprising a stationary member and a movable member, said stationary member having a shank engaging said opening and a slotted portion, means for attaching said movable member to said closure, and a pivot pin on said movable member for engaging said slotted portion, one marginal wall of said slot extending beyond the other for forming an abutment for limiting the opening movement of said closure and for holding said closure in open position.

3. A hinge for a display vessel comprising a stationary member and a movable member, said stationary member having a shank provided with a slotted head, said head having a plurality of recesses arranged on the arc of a circle with the bottom of the slot in the slotted head as a center, a movable member, a stud on said movable member for engaging said slot, and means on said movable member for engaging said recesses for holding said movable member in adjusted position.

4. In a hinge for display vessels, a hinge member comprising a stationary element and a movable element, one of said elements being provided with an open slot, a pivot pin carried by the other element for engaging said slot, means on one of said elements for engaging recesses on the other element for holding said movable element in a plurality of adjusted positions, and means for attaching said hinge to a display vessel.

5. In combination, a vessel of frangible material, a lug on said vessel, said lug having an opening therethrough, a closure for said vessel, a hinge for said closure, said hinge comprising a movable member, a stationary member having a threaded shank extending through said lug, a nut on said shank, a resilient element between said nut and lug, and means carried by one of said members for engaging the other member for holding said closure at any one of a plurality of adjusted positions.

6. In a hinge for a display vessel, a stationary part, means for attaching the same to a display vessel, a movable part, means for detachably connecting said movable part to said stationary part, and means for holding said movable part in a plurality of adjusted positions on said stationary part.

7. In a hinge for display vessels, a stationary part having a head portion provided with an open slot, a movable portion having a pivot pin for engaging said slot, and means for engaging said slot and said head for holding said movable member in lowered position or in various adjusted positions.

8. A hinge for a display vessel comprising a stationary member having a slotted head provided with a series of recesses in the arc of a circle about the lower portion of the slot, a movable hinge member, a pivot pin on said movable member for engaging said slot, a spring pressed detent for engaging said recesses for automatically locking said movable member in adjusted position and for engaging said slot for preventing removal of said movable member, means for connecting said stationary member to a vessel, and means for attaching said movable member to a closure for said vessel.

In testimony whereof I affix my signature.
RICHARD P. WHITE.
